DESIGN.

W. C. ANDERSON.
GLASS DISH.

No. 24,239.

Patented Apr. 23, 1895.

UNITED STATES PATENT OFFICE.

WILLIAM C. ANDERSON, OF TOLEDO, OHIO, ASSIGNOR TO THE LIBBEY GLASS COMPANY, OF SAME PLACE.

DESIGN FOR A GLASS DISH.

SPECIFICATION forming part of Design No. 24,239, dated April 23, 1895.

Application filed March 22, 1895. Serial No. 542,859. Term of patent 7 years.

To all whom it may concern:

Be it known that I, WILLIAM C. ANDERSON, a citizen of the United States, residing in Toledo, county of Lucas, and State of Ohio, 5 have invented and produced a new and original Design for the Ornamentation of a Glass Dish, of which the following is a specification.

This design, while relating generally to the ornamentation of glass-ware, more particularly 10 pertains to cut glass-dishes, the design being applicable on either side of the ware which more particularly comprises bowl-shaped dishes, plates and the like. The design is, however, usually applied upon the exterior of the dish.

The new and original design is illustrated in the accompanying drawings, in which—

Figure 1 is a bottom plan view of a bowl-shaped dish embodying the construction and 20 embellishment of the design. Fig. 2 is a cross sectional view.

The design is usually applied upon dishes which are substantially round, with however leaf pointed and sub-scalloped edges.

25 The leading characteristic of the design is produced by the approximately semi-circular arc lines, a, a, a, a , generated from centers which are at quarters around, and near the margin of, the dish, constituting the four intersecting ellipses, the conjugate diameters of which are radial, together with the second series of approximately semi-circular arc lines, b, b, b, b , having their centers intermediate between the centers from which the first 30 series of approximately semi-circular arcs is generated. Thus are produced, primarily, the four large radial ellipses, a^2, a^2, a^2, a^2 , the

long diameters of the pairs of which are coincident, and the intermediately arranged smaller radial ellipses, b^2, b^2, b^2, b^2 ; and secondarily by reason of the intersections the central square, 10, the proximate pentagons, 12, 12, 12, 12, outlying on the right diameters of the square, the pentagons, 13, 13, 13, 13, on the outwardly produced diagonals of the central square, which latter are within and at the inner end portions of the smaller radial ellipses, and the alternating larger and smaller leaf-pointed figures, 15, 16, bordering the design, and comprised within the outer portions of the aforesaid two sets of ellipses, a^2 . The figures thus produced have ornamentation which may be variable without departing from the primary characteristics of the design. As shown, the central square and the figures, 13 and 16, within the smaller ellipses, b^2 , are cross-hatched. The pentagons, 12, are stellated and the larger leaf-pointed figures, 15, 16, comprise the stellated rosettes, as shown.

60 The ornamentation produced in varying depths of cutting imparts an appearance of great richness and brilliancy to the dish and the design possesses great individuality, or a character peculiarly its own.

65 What I claim is—

The design for the ornamentation of a glass dish, substantially as herein shown and described.

WILLIAM C. ANDERSON.
